FLUORESCENT LIGHT TUBE ADAPTER

Alva H. McMullen, Miami, Fla.

Application October 31, 1939, Serial No. 302,260

2 Claims. (Cl. 248—1)

This invention relates to show case lighting, and more particularly to improved lighting equipment for store show cases.

A primary object of the invention is to provide an adapter or mounting element for fluorescent lighting tubes in show case reflectors, which will be convenient in design and durable and safe in use.

In the lighting of store show cases, it became a practice in some instances to utilize incandescent electric light bulbs of the conventional pear-shape Edison type, and to mount such bulbs in sockets attached to the interior of elongated concave reflectors, the bulb extending longitudinally and so received within the reflector as substantially to be concealed, while shedding its reflector-enhanced beam over the interior of the show case and the goods on display therein.

Thereafter an improved incandescent bulb of an elongated tubular design, having a substantially constant diameter, came into preferred use for show cases. This bulb, which was somewhat less in diameter than the conventional Edison bulb, became popular and a large proportion of modern show case equipment in use was fitted with reflectors of lesser diameter than formerly to accommodate the tubular incandescent element. Both the larger pear-shaped and the lesser tubular incandescent lighting elements had screw threaded bases which were received for mounting and electrical connection in internally threaded sockets ordinarily connected directly to the power supply circuit of the building.

Very recently fluorescent tubes have been in production for the lighting of show cases, such fluorescent tubes being gas filled lamps operating on a low tension voltage which is just below the high tension voltage on which neon lights operate. These fluorescent lights are an improvement over any other available lighting for show cases, among other reasons, because the light produced is a true or daylight beam. This new fluorescent lamp is available in elongated tubes corresponding generally in diameter with the tubular incandescent bulb referred to above, and by dimension is well adapted for use in the elongated reflectors customarily used heretofore in show cases.

Inasmuch as the new fluorescent tube lamps require a different voltage they cannot operate on the regular electric circuit intended for the former Edison type incandescent lamp, but are connected through a transformer to the current supply. Instead of the spirally threaded base which characterizes the incandescent type lamp,

these fluorescent tubes have terminals at each end, each terminal having two prongs. For connection in the circuit it is requisite that suitable connections be provided to enable each prong at the ends of the fluorescent tube to be connected to the supply beyond the transformer.

Although new reflectors complete with appropriate connections are on the market, in some instances such new reflectors are unsatisfactory because they are of too large a diameter; in addition, requirement is evident for an easily installed and detachable adapter which will enable use of the new and desirable fluorescent tube lamp in the elongated concave reflectors with which practically all show cases are at present equipped.

It is another object of the invention to provide an adapter which will include simple and inexpensive provision for conveniently mounting fluorescent tube lamps in reflectors of large or smaller concave radius.

The above and additional objects and advantages of the invention will be apparent from a consideration of the following detailed description, read in connection with the accompanying drawings forming a part thereof, wherein

Fig. 1 is a fragmentary perspective forward looking view of the interior of a conventional glass show case of the type used in department stores, said view being taken from the back of the case and looking toward the front of the top thereof.

Fig. 2 is an enlarged diagrammatic view of a reflector of the elongated concave type carrying adapters in embodiment of the invention, and indicating a conventional circuit arrangement for supplying the lamps.

Fig. 3 is a front view of the adapter for use in one present standard type reflector, such as the T-10 type.

Fig. 4 is an end view of the adapter shown in Fig. 3.

Fig. 5 is a rear view of the adapter of Fig. 3, fitted in the reflector.

Fig. 6 is a front view of the adapter for use in another and smaller type reflector, such as the T-6½ type.

Fig. 7 is an end view of the adapter shown in Fig. 6.

Fig. 8 is a rear view of the adapter shown in Fig. 6.

Fig. 9 is a top view of the adapter shown in Fig. 6.

Fig. 10 is a front view of a fluorescent light tube extractor member.

Fig. 11 is a sectional view taken on the line 11-11 of Fig. 3.

Fig. 12 is a front view of the adapter of Fig. 3 showing an insulator cover in place.

Fig. 13 is a side view of the insulator cover of Fig. 12.

Fig. 14 is a sectional view on the line 14-14 of Fig. 12.

Referring to the drawings wherein similar parts are indicated by identical reference numerals, a conventional department store show case 20 is of the rectangular type having a flat plate glass top 21, a plate glass front 22, and, at each end, a plate glass end 24. These several plates of the cabinet are connected by conventional metal angle supports 25, said angle supports being carried by the flat floor 26 of the show cases. On the inside of the show case, at the point of intersection of top 21 and front 22, is provided an elongated reflector 27 comprising a concave frame 28 carrying a concave polished liner or mirror element 29. Supported in the concavity of frame 28 is a fluorescent lamp 30 consisting of a gas filled glass tube carried in opposite adapters 32-32 by a connector 33 fixed to the lamp 30 and carrying two prongs 34-34 at each end of the fluorescent lamp.

The cathodes of fluorescent lamp 30 have to be heated by the electrical current before the arc will strike or establish its path through the gas. This requires a choke coil and an automatic switch, both designated by transformer 36, (Fig. 2) in each individual lamp circuit. Transformer 36, which may for convenience be carried on the floor of the show case, serves to disconnect the heating current when the arc is established, hence a four-wire hook up between lamp 30 and transformer 36 is shown. As presented, the circuit includes left end conductors 37a and 37b, and right end conductors 38a and 38b communicating with prongs 34-34 on the corresponding ends of lamp tube 30. The circuit is completed to any conventional power supply 40.

An important feature of the present invention consists of the design of adapters 32. Said adapters include an inner body 41 formed of insulating material such as porcelain, Bakelite, rubber, or thermoplastic material, and has a front 42 and back 44. Its curved exterior portion 43 is preferably shaped to correspond with the concave curvature of the reflector frame and is finished with a guiding fin 48 at each side for reception in inturned flanges 48 at opposite edges of the reflector frame. Spaced recesses 49-49 in front 42 receive prongs 34-34 and are defined by shoulders 50-50 each supporting a spring contact 52 extending into the recess 49 for making contact with prong 34. Lug portions 53 on contacts 52 lie in a top recess 54 for receiving conductors, such as conductors 37a and 37b, as seen in Fig. 2. Lugs 53 are secured by screw binding posts 56 engaged in screw threaded recesses 57 for secure engagement by the ends of the conductors. Externally, body 41 has opposite lateral recesses 58-58 for retaining the conductors flat against the inner surface of the reflector frame. Bowed bottom 60 of body 41 carries an elongated clamping member 61 having terminal hooks 62 at each end for locking engagement with the flanges 48 of the reflector frame. Clamping member 61 has a center hole 63 for a retaining screw 64 which may be tightened for assembly in threaded recesses 65 in body 41.

Fluorescent lamps are described for size to the trade with respect to their diameter as well as type, the letter "T" being used to designate the tubular style, while the diameter in eighths of an inch is expressed numerically. Thus, "T-6½" would mean to anyone skilled in the art a tubular element approximately $\frac{1}{2}$ of an inch in diameter.

From the foregoing it will be observed that when it is desired to install a fluorescent lamp 30 in one of the smaller conventional reflectors, such as that known in the trade as type T-6½, the assembly indicated in Fig. 8 will obtain. Therein, the body 41 forms a complete adapter which may be adjusted slidably longitudinally 10 of said smaller reflector frame to proper position with respect to the length of lamp 30. The lamp may then be connected by inserting prongs 34 in recesses 49, thereby establishing electrical contact for the left end of the lamp with spring contacts 52 and electrically interconnected conductors 37a and 37b. These conductors lead along the inner surface of the reflector being accommodated in lateral recesses 58. Fixing of the adapter in position is then attained simply 15 by tightening screw 64 to bind clamp 61 upon the flanged edge 48 of the reflector frame. When the right hand end of lamp tube 30 is connected in a right hand adapter of the type shown in Figs. 6 to 8 and in electrical communication with right end conductors 38a and 38b the lighting installation for such a smaller sized reflector is complete.

Another important aspect of the invention is the provision of enlargement shells 68 of insulating material. Enlargement shell 68 may be used to complete the adapter for convenient assembly 35 in a larger type of reflector frame such as that commonly referred to as type T-10. Enlargement shell 68 corresponds in thickness with inner body 41 and has an inner concave surface 69 for snugly receiving body 41, being characterized by opposite locking shoulders 70-70 for closing the lateral recesses 58 of body 41. Enlargement shell 68 has an outer convex surface 40 shaped substantially to coincide with the inner concave surface of said larger type reflector frame and is formed with opposite lateral recesses 73-73 for retaining conductors flat against said reflector.

For fixing enlargement shell 68 on body 41 the shell has opposite screw threaded recesses 74 communicating with screw threaded recesses 75 on body 41 through which extend screws 76 which may be readily tightened to form a rigid assembly 45 functioning as an adapter unit. An elongated clamping member 78 has terminal hooks 79 for locking engagement with edge flanges 48 of said larger type reflector frame. Clamping member 78 has a center hole 80 for attaching screws 64. Opposite apertures 82 extend transversely in enlargement shells 68 for accommodating the conductors to be attached to screw binding posts 56-56 therein.

For a finished assembly when desired a cover plate 83, see Figs. 12 to 14, may be used, said cover plate fitting over the front of inner body 41 and being attached by a screw 84. This cover plate is characterized by spaced notches 85-85 for reception of prongs 34-34.

As a further finishing implement a separator plate 87, see Fig. 10, may be employed. This separator plate corresponds in circumference generally to fluorescent lamp 30 and has spaced apertures 88-88 for receiving prongs 34-34. An 70 integral ear 89 depends from the lighting fixture 75

and may be manually grasped to assist in extracting the tube from the adapter when desired.

From the foregoing it will be observed that the adapters presented may be utilized to fit either the larger or smaller conventional styles of reflectors and being readily adjustable longitudinally with respect to the frames will enable convenient, safe and economical mounting therein of tubular fluorescent lamps.

What I claim is:

1. An adapter for fluorescent tube lamps comprising coplaner interfitting outer and inner bodies of insulating material, the inner body having a recess for receiving fluorescent tube connector prongs, spring contacts mounted on the inner body and extending in said recess, terminal posts in the inner insulating body connected to said spring contacts, communicating apertures in said inner and outer insulating bodies for conductors connectible to said posts, a recess at the exterior of said outer insulating body for re-

ceiving said conductors in nesting relationship therewithin, clamping means, and means on said inner insulating body for retaining said clamping means.

- 5 2. In a device of the character described, a flat body of insulating material having a portion of its periphery substantially convexly arcuate and a connecting portion thereof relatively flat with spaced transverse fins, said body having a recess for receiving fluorescent tube connector prongs and housing spring contacts fixed to the body; such body also being shaped to include a peripheral recess spaced from said first mentioned recess, conductor-end terminal posts in said peripheral recess and connected to said spring contacts, said body also having a lateral recess at each end of said peripheral recess for receiving conductors in nesting relationship therewithin, a clamping element and means on said relatively flat portion between said fins for retaining said clamping element.
